UNITED STATES PATENT OFFICE.

JOHN B. JOHNSON, OF SAN FRANCISCO, CALIFORNIA.

WINDOW-WIPING DEVICE.

1,362,801.

Specification of Letters Patent. Patented Dec. 21, 1920.

Application filed January 21, 1919. Serial No. 272,286.

To all whom it may concern:

Be it known that I, JOHN B. JOHNSON, a citizen of the United States, residing at the city and county of San Francisco and State 5 of California, have invented certain new and useful Improvements in Window-Wiping Devices, of which the following is a specification.

The present invention relates to that type 10 of window cleaning device wherein a longitudinally disposed strip of rubber, ordinarily termed a "squeegee" is employed as the wiping material for making contact with the surface of the window to be cleaned, and 15 which form of cleaning device is that commonly employed by window-cleaners generally for removing the moisture and dirt from the surface of the windows of stores, hotels and office buildings. In this type of 20 window cleaning devices the squeegee is firmly and immovably fixed within the T-member of the head of the device, with the result that on the wearing out or a mutilation 25 of the strip of rubber or squeegee the entire head is rendered useless and has to be thrown away. Inasmuch as the head attachment of each cleaning device costs approximately seventy-five (75¢) cents, it will 30 be seen that on the wearing out or mutilation of the strip of rubber or squeegee considerable loss is occasioned by having to throw away the entire head structure.

The object of the present invention is to dispense with the loss of the entire head 35 structure on the wearing out of the squeegee thereof, and which, where a considerable number of cleaning devices are utilized, as for instance, where a number of operators or window cleaners are employed by a given 40 company, runs into considerable money per year, which object is attained by so constructing the T-member of the head of the cleaning attachment as to permit or allow of a squeegee carrying member or holder to 45 be slidably united to the T-member of the head of the attachment, so that on a wearing-out or the mutilation of the rubber strip or squeegee the securing holder carrying the same may be removed from within the T- 50 member of the head of the cleaning device and a new squeegee, with its securing member or holder readily substituted for the removed worn out or mutilated squeegee. As the slide securing member or holder for 55 the squeegee can be manufactured and sold at a nominal expense, approximately twenty-

five cents (25¢) it is apparent that only a fraction of the cost of a head is required to be expended for the replacement of a worn-out or mutilated squeegee.

To comprehend the invention reference should be had to the accompanying sheet of drawings, wherein,

Figure 1 is a perspective view partly broken away of an ordinary window cleaning device with the invention applied thereto.

Fig. 2 is a similar view of the slide holder for the head with the squeegee secured thereto.

Fig. 3 is an enlarged detailed view taken on the line x—x Fig. 1 of the drawings.

In the drawings, the numeral 1 is used to indicate any suitable form of a handle for the cleaning attachment and to which the head is removably applied, the said head consisting of a shank member 2 and a transversely disposed T-member 3. The T-member 3 is formed from a single piece of metal so shaped as to provide a longitudinally disposed groove or channel 4, and a rearwardly projected guide groove 5, the guide-groove 5 being formed by the rib-shaped extension 6, of the head member 3. The longitudinal guide-groove 4 of the member 3 is adapted to slidably receive a securing member or holder 7, which is formed from a single piece of metal stamped as to provide an outwardly projected rib 8, which rib on the slide member or holder 7 being inserted within the groove or channel 4 of the member 3 fits within the guide groove 5 of the rib 6, said rib 8 thus serving as the means for locking the member 7 to the T-member 3 of the head, that is, holding the same against displacement by pressure applied to the squeegee thereof during the operation of the attachment. There is clamped between the wall members and the slide holder 7 a rubber strip or squeegee 9 which has applied to the back thereof and held between the walls of the slide holder a yielding or resilient strip 10, formed of celluloid or other suitable material, which is adapted to give under pressure applied to the face of the squeegee, and the spring or tension of which causes the squeegee to be restored to its normal position on the pressure being released therefrom.

The squeegee with its yielding backing 110 plate which is of a width slightly less than the width of the squeegee is held within the

- slide holder 7 in any suitable manner, preferably by compressing the wall members of the holder to firmly bear against the wall surfaces of the squeegee and backing plate 5 10. As thus secured the slide holder 7 with the squeegee 9 and backing plate 10 constitute a unitary structure and one which is easily applied to or removed from the **T**-member 3 of the head of the cleaning device. 10 Under the construction as herein described, it is apparent that as the squeegee becomes worn out or mutilated to such an extent as to be rendered useless for cleaning purposes it is only necessary to remove the slide 15 holder 7 from the **T**-member 3 of the head of the attachment and to substitute therefor a new slide holder with a squeegee and yielding backing plate applied thereto, the only loss or waste occasioned on the wearing out 20 of the squeegee being the cost of the squeegee with the yielding backing plate and slide holder 7, the balance of the head of the cleaning attachment being serviceable for future use. The loss heretofore incident to 25 the throwing away of the entire head structure being thus eliminated, the worn out squeegee with its associated parts representing only a fraction of the cost of the entire head structure. Under this arrangement, 30 the head structure of the cleaning device may be used indefinitely, or for the life of an indefinite number of squeegees.
- The slide holder with the squeegee and backing plate may be supplied in number, as 35 for instance packages of one dozen in connection with the sale of each window cleaning device, so that the user of the attachment may have on hand a number of squeegees to be substituted as the one supplied with the 40 head structure of the cleaning device becomes worn out, or the slide holder with its associated parts may be purchased separately as desired for replacement of the worn out squeegee.
- 45 While the invention has been described and illustrated in its preferred embodiment

thereof, I do not wish to be understood as being limited thereto, but, on the contrary desire to claim as broadly as the state of the art will permit the application to the **T**-member 50 of a head attachment of a window cleaning device of a holder slidably mounted therein for removal purposes, said holder carrying a squeegee with its yielding backing plate. 55

Having thus described the invention what is claimed as new and desired to be protected by Letters Patent is:

A window cleaner consisting of a head 60 formed of a strip of spring metal bent to a substantial **U**-shape in cross section to provide wall members having parallel inner faces connected by a yielding base portion, one wall being provided with a longitudinally disposed outwardly projecting guide 65 groove open at its opposite ends, a wiper strip holder formed of a strip of sheet metal receivable within said head by an endwise telescoping movement, and of a cross sectional configuration corresponding to that of 70 the head, the outer surface of the guide groove of said wiper strip holder providing a rib for reception in said guide groove of the head, a flat wiper strip held between the parallel inner face of said holder through 75 frictional contact therewith and insertible therein and removable therefrom through the longitudinal opening therein, and a flat flexible backing strip of resilient material positioned between the inner surface of one 80 wall of said holder and the upper surface of said strip with its forward edge projecting beyond the longitudinal side edges of said head and holder and falling short of the outer edge of said strip. 85

In testimony whereof I have signed my name to this specification in the presence of the subscribing witness.

JOHN B. JOHNSON.

Witness:

D. B. RICHARDS.
